DESIGN FOR A PIANO

Louis Bromberg, Rockaway Park, N. Y.

Application March 17, 1947, Serial No. 137,691

Term of patent 14 years

(Cl. D56—9)

To all whom it may concern:

Be it known that I, Louis Bromberg, a citizen of the United States of America, resident of Rockaway Park, county of Queens, and State of New York, have invented a new, original, and ornamental Design for a Piano, of which the following is a specification, reference being had to the accompanying drawing, forming part thereof.

Fig. 1 is a perspective view of a piano showing my new design; and

Fig. 2 is a fragmentary top plan view of the piano shown in Fig. 1.

The other side of the piano has an appearance corresponding to that of the side shown, and the back of the piano has the appearance of any conventional upright piano.

The drawings are shaded to show contrasting appearance of various parts of the piano.

I claim:

The ornamental design for a piano, as shown and described.

LOUIS BROMBERG.
